E. B. STIMPSON.
CARTRIDGE BELT.
APPLICATION FILED MAY 9, 1918.
1,288,261.

Patented Dec. 17, 1918.

Edwin Ball Stimpson
by his Attorney
Abel L. Brownrigg.

UNITED STATES PATENT OFFICE.

EDWIN BALL STIMPSON, OF BROOKLYN, NEW YORK.

CARTRIDGE-BELT.

1,288,261.

Specification of Letters Patent. Patented Dec. 17, 1918.

Application filed May 9, 1918. Serial No. 233,553.

To all whom it may concern:

Be it known that I, EDWIN BALL STIMPSON, a citizen of the United States, residing at Brooklyn, in the county of Kings and State of New York, have invented certain new and useful Improvements in Cartridge-Belts, of which the following is a specification.

My invention relates to cartridge belts of the particular type that is adapted for use in feeding cartridges to the loading mechanism of machine guns.

Cartridge belts of this general nature such as have been heretofore known in the art have invariably been constructed of comparatively thick and heavy material of a woven texture that not only added considerably to the volume occupied by the packed cartridges, but also added very materially to the expense of manufacture. It will be apparent that it is of prime importance that the bulk taken up by the cartridge supply be restricted as far as possible because of the transportation difficulties that arise in the operation of the machine guns in the advanced and exposed positions in which they are usually mounted in modern methods of warfare. It is also important that the cost of manufacture of the belt be kept as low as possible consistent with the retention of the requisite strength to insure the unfailing supply of the belt carried cartridges to the feeding mechanism of the guns. The rapid operation of the guns on a large scale uses up great quantities of cartridges and belts and where, as is often the case, the salvaging of emptied belts is rendered difficult or impossible, it will be seen that the wastage of material adds enormously to the expense of producing this form of cartridge belt.

The main object of the present invention is to provide a cartridge belt made of comparatively thin and inexpensive material in order that the objections pointed out as being attendant upon the use of belts as known and used in the prior art may be to a great extent eliminated.

With this and other objects in view, one feature of the invention consists in the provision of a cartridge belt constructed of comparatively unsubstantial and inexpensive sheet material, such as paper or light cotton or other fabric, and having means included therein for substantially reinforcing said belt in a plurality of zones along its length.

A further feature of the invention con-

templates the attachment of two strips of material of the character referred to to each other at separated intervals along the reinforced zones to thereby form cartridge holding loops between the points of attachment.

Another feature of the invention consists in the use of cords or threads as reinforcing members and embedding the cords between folded or doubled over strips of the material to thereby form a belt member having the requisite strength, and in arranging two such members in a face to face relation and in stitching the corresponding threads of the respective members to each other at intervals to form cartridge holding loops.

Another feature of the invention resides in the use of metallic clip members for attaching the belt members to each other to form the cartridge holding loops.

Still another feature of the invention resides in providing longer points of attachment of the members to each other at one edge of the belt than the other so as to provide loops correspondingly reduced in size to fit the smaller end of the cartridge.

Other features of the invention will be hereinafter described.

In the drawings,

Figure 1 is a view of a portion of a cartridge belt embodying a preferred form of the invention and showing a number of cartridges in place therein.

Fig. 2 is an enlarged sectional view taken along the line 2—2 of Fig. 1.

Fig. 3 is a sectional view taken at right angles to the view shown in Fig. 2 and along the line 3—3 of Fig. 1.

Fig. 4 is a fragmentary view of a belt showing a modified form of the invention.

Fig. 5 is an edge view of the form of belt shown in Fig. 4.

Fig. 6 is a fragmentary view of still another modification of the invention.

Fig. 7 is an edge view of the form of belt shown in Fig. 6.

Fig. 8 is a sectional view taken along the line 8—8 of Fig. 6.

Fig. 9 is a sectional view of one of the strips comprising the form of belt shown in Fig. 6.

The cartridge feeding belt shown in the drawings comprises the strips 1 and 2 formed of any suitable sheet material of an unsubstantial and inexpensive nature, such as paper or light cotton or other fabrics, and having the cords or threads 3 embedded

therein for the purpose of increasing the tensile strength of the belt as a whole. The cords 3 are preferably arranged at the two lateral margins of the strips and along the central axis thereof, so that an ample margin of strength is provided to withstand the operation of the feeding mechanism and prevent the breaking of the belt as it is drawn through the breech mechanism to provide for the feeding of the cartridges therefrom into the chamber of the gun.

In order to provide loops or pockets in the belt structure in which the cartridges may be received, the two strips of material 15 1 and 2 are attached together at the proper intervals to provide loops of the desired size by means of groups of stitches 4 and 5 that are arranged to embrace the corresponding separated portions of the reinforcing cords 20 and the particular portions of the sheet material in immediate contact therewith. It will be seen that the stitched portions 5 of the lower cord 3 in Fig. 1 occupy a greater space than the corresponding stitched portions 4 in order to provide for closely fitting the reduced end portions 6 of the cartridges 7.

While in the preferred embodiment of the invention three reinforcing cords are used, 30 as shown in Fig. 1, it is possible to make use of but two cords as indicated in Fig. 4 of the drawing. With this form of construction the cartridge is held at only two points near the ends and the entire length 35 of the cartridge intermediate thereto is loosely held so as to offer a minimum degree of resistance to the operation of removing the cartridges from the corresponding loops in the belt.

40 In the two forms of the invention already described it will be seen by reference to Figs. 2 and 3 that each main strip 1 and 2, making up the two members of the belt, consisting of doubled over strips 8 and 9 of the material folded over on themselves and having the cord members 3 interposed between them. The parts making up the main strip members 1 and 2 as thus described are preferably maintained in their relative positions 45 by means of any suitable adhesive material.

50 As a modification of the foregoing and in order to employ but a single thickness of material in either belt strip, where the character of the material so warrants, a construction such as is shown in Figs. 6 and 9 may be employed, in which a strip of material is folded over only at its lateral margins as at 10 and 11 for a sufficient breadth to adequately cover the two reinforcing cords 3. 55 It will also be seen that in Figs. 6, 7 and 8 a different means for attaching the strips together than that shown in Fig. 1 has been employed and that takes the form of the metal clip members 12 and 13. Following 60 the construction shown in Fig. 1, the mem-

bers 12 are not so wide as the members 13, so that different size loops are provided to fit the different diameters of the cartridge.

It will be seen that a cartridge belt has been provided that may be constructed of 70 unsubstantial and inexpensive material such as paper, and which will nevertheless offer an adequate resistance to being torn as it is drawn through the feeding mechanism of a gun.

75 Having thus described my invention, what I claim and desire to secure by Letters Patent of the United States is:

1. A cartridge belt comprising: two strips of paper placed face to face and having 80 reinforced zones extending longitudinally thereof, and means for attaching said strips to each other at intervals along said reinforced zones to thereby form cartridge holding loops between said points of attachment.

2. A cartridge belt comprising: two strips of paper arranged face to face and having reinforced lateral edges, and means for attaching said strips to each other at intervals 90 along said reinforced edges to thereby form cartridge holding loops between said points of attachment.

3. A cartridge belt comprising: two strips of paper laid face to face and having members 95 extending longitudinally thereof to form reinforced zones of substantial strength therein, and means for attaching said strips to each other at intervals along said reinforced zones to thereby form cartridge holding loops between said points of attachment.

4. A cartridge belt comprising: two strips of paper laid face to face and having cords embedded in the lateral edges thereof to form reinforced zones of substantial 105 strength therein, and means for attaching said strips to each other at intervals along said reinforced lateral edges to thereby form cartridge holding loops between said points of attachment.

110 5. A cartridge belt comprising: two strips of paper having cords affixed thereto along the length thereof, said strips being arranged in face to face relation to each other with the cords of one strip lying closely adjacent to the corresponding cords on the other strip, and said adjacently arranged cords being stitched to each other at intervals to thereby form cartridge holding loops.

115 6. A cartridge belt comprising: two strips of paper, each strip having folded edges, reinforcing cords embedded in said folded edges, said strips being arranged in face to face relation to each other with the cords of one strip lying closely adjacent to the cords of the other strip, and said adjacently arranged cords being stitched to each other at intervals to thereby form cartridge holding loops.

7. A cartridge belt comprising: two strips of paper having members with a comparatively high tensile strength embedded therein to form reinforced zones extending longitudinally along the lateral edges thereof, said strips being arranged in face to face relation to each other with the reinforcing members of one strip lying closely adjacent the reinforcing members of the other strip, 10 said adjacently arranged members and the adjoining portions of the strips being stitched to each other at intervals to thereby form cartridge holding loops, and said stitched portions along one edge of said belt being of greater length than the corresponding stitched portions along the opposite edge of the belt.

8. A cartridge belt comprising: two strips

of paper, each strip being folded over on itself, and having reinforcing members embedded between the folds and extending longitudinally thereof.

9. A cartridge belt comprising: two strips of paper laid face to face and having reinforced zones extending longitudinally thereof, and means for attaching said strips to each other at intervals along said reinforced zones to thereby form cartridge holding loops between said points of attachment, those portions of the strips between the reinforced zones being unattached to each other.

Signed at Brooklyn, in the county of Kings, and State of New York, this 2d day of May, 1918.

EDWIN BALL STIMPSON.
